1 Claim

ABSTRACT OF THE DISCLOSURE

A pipe seal unit for use in cementing pipe in the well bore for preventing leakage along the interface between the outside surface of the pipe and the inside surface of the cement, after cementing is completed. It includes two fixed rings mounted about the outside of the pipe, each of which supports an elastomeric sealing element which have spaced apart lips and means for maintaining the spaced apart relationship whereby the fluid migrating either upwardly or downwardly along the outside surface of the pipe and the inside surface of the cement is sealed off.

This invention relates to an apparatus for use in cementing pipe such as a casing in a well bore to prevent fluid movement along the casing-cement interface.

During oil well drilling operations, quite often it becomes necessary to cement a portion of the casing in the well bore so that production can be taken from different levels in the well and without the various levels contaminating each other. For example, it might be desirable to perforate the casing at one level wherein the formation pressure is substantially lower than an adjacent level and which adjacent level it is desired to maintain in an unchanged condition. The result is that there will be a tendency for the fluid of the higher pressure zone to migrate along the pipe at the cement-pipe interface. The seal unit of this invention is designed to prevent such migration.

Recent investigations have uncovered the fact that many casing-cement interfaces have been subjected to bond failure and fluid movement therestat at lower pressure differentials than is often desired, particularly in depletion type reservoirs or where stimulation (acidizing, fracturing) methods require high injection pressures. Communication at the cement-casing interface, like in the remainder of the casing-hole annulus, will prevent efficient depletion of a producing zone or cause stimulation work to be ineffective due to uncontrolled migration in the annulus.

Certain prior art sealing units have been developed in an attempt to solve this problem, but none of which have been completely successful for various reasons including inefficient stoppage of the migration, early failure, and the like.

It is, therefore, an object of this invention to provide an improved pipe sealing unit for use in cementing pipe in the well bore, which unit solves the foregoing problem and overcomes the shortcomings of the prior art.

Briefly stated, this invention includes a lower annular backup member, preferably in the form of a metal ring having an upwardly facing shoulder and having means for fixedly securing the ring about the pipe or casing to be cemented. It also includes an upper annular backup member, preferably in the form of a metal ring having means for fixedly securing the ring about the pipe. A pair of elastomeric annular sealing elements are mounted about the pipe or casing and between the backup members, with each of the sealing elements having an annular channel forming a generally U shaped axial end, which

2

ends are mounted in facing relationship with the opposite ends thereof held in abutting relationship with an adjacent backup member. In addition, spacing means are mounted about the pipe or casing and between the U shaped axial ends of the sealing elements for maintaining a space therebetween. It is to be understood that a plurality of these sealing units may be used for each cementing operation and can be axially spaced apart on the casing.

Reference to the drawing will further explain the invention wherein like numerals refer to like parts and in which:

FIG. 1 is a side elevation view of the apparatus of this invention shown mounted on a casing pipe which casing pipe is shown cemented in a well bore.

FIG. 2 is a vertical sectional view, somewhat enlarged, of the apparatus shown in FIG. 1.

The apparatus includes a lower annular backup member in the form of lower ring 11 of metal or other suitable material mounted about casing pipe 12 and fixedly held thereto as by a plurality of set screws 13.

The apparatus also includes an upper annular backup member in the form of upper ring 16 of metal or other suitable material which is fixedly secured about casing 12 at an axially spaced apart position from ring 11 and is fixedly secured to casing pipe 12 as by a plurality of set screws 13. Lower ring 11 has an upwardly facing abutting surface and upper ring 16 has a downwardly facing abutting surface and between said abutting surfaces there is mounted a pair of elastomeric annular sealing elements in the form of upper and lower annular rubber seals 19 and 20.

Each of the seals 19 and 20 have an annular channel forming a generally U shaped axial end, which form a pair of spaced apart lips, with the lips held in facing relationship. The opposite axial ends of seals 19 and 20 are held in abutting relationship with the adjacent abutting shoulders of metal rings 16 and 11, respectively.

Spacer means are mounted about the pipe and between the U shaped axial ends of seals 19 and 20 for maintaining a space therebetween. The spacer means conveniently take the form of an annular ring 22 having a diameter greater than the outside diameter of pipe 12 and having an axial length greater than the combined depths of the channels in seals 19 and 20, whereby seals 19 and 20 are held in spaced apart relationship.

It is to be understood that spacing ring 22 does not perform a sealing function itself and therefore may be perforated or have holes therein, such that fluid pressure may pass therethrough and be applied against either the inside or outside lips of each of the seals 19 and 20.

The unit is operated by installation on casing pipe 12 by first slipping upper metal ring 16 over the lower end of pipe 12 and moving it axially upward to the desired position where it is secured in place by set screws 13 in a fixed relationship with pipe 12. Thereafter, upper rubber seal 19, spacer ring 22 and lower seal 20 are fitted over the lower end of pipe 12 and slid up in abutting relationship with upper ring 16, as shown in FIG. 2. Care must be taken to insure that the channels or U shaped ends of seals 19 and 20 are facing each other and that ring 22 is inserted in the channels as shown.

Thereafter, lower metal ring 11 is fitted over the end of pipe 12 and moved up into abutting relationship with lower seal 20 as shown, and thereafter secured fixedly in position by tightening of set screws 13. Wetting the surface of pipe 12 with a soapy solution or diesel oil will facilitate the sliding of seals 19 and 20 therealong.

In fixedly securing rings 11 and 16 to pipe 12, care must be taken that they are spaced uniformly thereabout and the abutting ends thereof are generally perpendicular

with the circumferential surface of pipe 12. When the unit is to be attached to casing having upset tool joints, it is necessary to stretch seal elements 19 and 20 over the upset and to weld ring halves on opposite sides thereof to form rings 11 and 16. Alternatively, rings 11 and 16 may be formed with hinged halves having appropriate locking means. Thereafter, the components can be pushed together to the position shown in FIG. 2. With the unit thus installed, the casing is run into the bore hole and cemented into place as shown in FIG. 1, by cement 23.

It is to be understood that a plurality of these sealing units can be installed on a casing and should preferably be installed immediately above and below the intervals to be perforated. Although the resistance to fluid flow is not theoretically increased by using multiple units, it is recommended that at least two units be spaced five feet apart and above the perforation zone and two additional ones also spaced about five feet apart below each zone to allow for possible variation in pipe measurements, etc. Further, the use of a casing centralizer either immediately 15 above the units or below the units would also assure a uniform sheath of cement around the unit as well as providing some protection to the unit while being run into the hole.

In addition to properly locating the units above and 25 below the zones to be perforated, the successful operation of the units is further insured by a good uniform cement job in which both the circulatable and non-circulatable mud media is effectively displaced by the cement slurry using proven cementing procedures and equipment, as is 30 well-known to those skilled in the art.

It is presently thought that the sealing unit as taught herein is more successful than prior art units because of its novel construction. It is thought that the novel arrangement of seals 19 and 20 prevents migration along pipe 12 35 in either the upward direction or downward direction. Lower seal 20 prevents downward migration and upper seal 19 prevents upward migration. It is believed that this occurs because any pressure in the space between seals 19 and 20 causes the lips thereof to be projected radially inwardly and outwardly respectively to sealing engagement with adjacent surfaces. This occurs because 40 of the cup-shaped construction of seals 19 and 20 whereby the pressure causes the lips to move in the radial directions noted above.

Applicant's unit does not require special pipe surface preparation such as sand blasting or chemical removal of mill varnish. It does not require excessive differential pressure on the cement (between the annulus and the inside of the casing) while curing.

Applicant's unit responds mechanically to any fluid movement from either direction, i.e., above or below.

The mechanical sealing action of applicant's invention is not affected by the thermal expansion and contraction of the pipe due to the cement's heat of hydration while 55 curing.

Since seals 19 and 20 are free from and not attached

to the adjacent back up rings 16 and 11 respectively, the seals are able to center themselves for efficient sealing.

Applicant's sealing unit can be used on upset casing by stretching the elastic seals 19 and 20 over the upset, thereafter splitting and rewelding the steel backup rings 16 and 11 about the pipe and thereafter assembling as shown in FIGS. 1 and 2. Alternatively, and as noted above, hinged backup rings may be used which have appropriate latch means.

What is claimed is:

1. In apparatus sealing fluid flow between a cemented well casing in a well bore and the cement, the combination comprising:
  - a lower backup ring mounted about said casing, said lower backup ring having an upwardly facing shoulder and a plurality of set screws fixedly securing said lower backup ring about said casing;
  - an upper backup ring mounted about said casing, said upper backup ring having a downwardly facing shoulder and a plurality of set screws fixedly securing said upper backup ring about said casing at a position axially spaced apart from said lower backup ring;
  - a pair of unitary elastomeric annular sealing elements mounted about said casing and between said backup rings, each of said sealing elements having an annular channel in one end thereof forming inner and outer lips, with the lips of one of the said sealing elements supported in spaced apart and facing relationship to the lips of the other of said sealing elements, said elements being entirely of elastomeric material and each of said elements having an abutting end opposite from the end having said channel, said abutting ends engaging an adjacent one of said shoulders of said backup rings in non-attached abutting relationship and radially outwardly movable with respect thereto;
  - and an annular spacer ring mounted about said casing and in said channels of said sealing elements and maintaining said spacing between said elements, said annular spacer ring having opening means for passing fluid between opposite sides thereof.
